(57) **CLAIM**

The ornamental design for a vehicle rear upper bumper cover, as shown and described.

DESCRIPTION

FIG. 1 is a front elevational view of a vehicle rear upper bumper cover showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The ghosted or low contrasted showing of the vehicle rear upper bumper cover is provided for the purposes of illustrating environmental structure and forms no part of the claimed design.

1 Claim, 7 Drawing Sheets
